CIRCULAR CRIB

Taylor F. White, Longwood, Fla.
(11004 Cedar Creek Road, Louisville, Ky. 40229)

Filed Aug. 21, 1972, Ser. No. 282,472

Term of patent 14 years

Int. Cl. D6—01

U.S. Cl. D6—16

FIG. 1 is a perspective view of a circular crib showing my new design with the gate in the lower position; FIG. 2 is a top plan view, and

FIG. 3 is an elevational view with the gate in a raised position.

I claim:

The ornamental design for a circular crib, substantially as shown and described.
